UNITED STATES PATENT OFFICE

166,371

RECORD CHANGER TURNTABLE UNIT

Samuel E. Adler and James E. Vistain, Jr.,
Chicago, Ill.

Application December 5, 1951, Serial No. 17,624

Term of patent 14 years

(Cl. D56—4)

To all whom it may concern:

Be it known that Samuel E. Adler and James E. Vistain, Jr., citizens of the United States, residing at Chicago, in the county of Cook, State of Illinois, have invented a new, original, and ornamental Design for a Record Changer Turntable Unit, of which the following is a specification, reference being had to the accompanying drawings, forming part thereof.

Fig. 1 is a top plan view of a record changer turntable unit, showing my new design;

Fig. 2 is a front elevational view thereof;

Fig. 3 is an elevational view of the same looking from right to left; and

Fig. 4 is an elevational view of the record changer looking from left to right.

We claim:

The ornamental design for a record changer turntable unit, as shown.

SAMUEL E. ADLER.
JAMES E. VISTAIN, JR.
